UNITED STATES PATENT OFFICE.

ARION S. KALENBORN AND AUGUST J. PAHL, OF SAN FRANCISCO, CALIFORNIA,
ASSIGNORS TO K-P-E-ELECTRIC CO., A CORPORATION OF CALIFORNIA.

HIGH-TENSION DISCONNECTING-SWITCH.

1,081,671.

Specification of Letters Patent. Patented Dec. 16, 1913.

Application filed December 30, 1911. Serial No. 668,655.

To all whom it may concern:

Be it known that we, ARION S. KALENBORN and AUGUST J. PAHL, citizens of the United States, residing at San Francisco, 5 in the county of San Francisco and State of California, have invented certain new and useful Improvements in High-Tension Disconnecting-Switches, of which the following is a full, clear, and exact description.

10 This invention relates to high tension electric disconnecting switches and has for one of its objects the construction of a switch of this type which shall be more economical of construction than like devices, 15 adapted to meet corresponding conditions, as heretofore constructed.

Another object of the invention is to so dispose the di-electric parts of the appliance that they may be adapted to not only withstand the disruptive electrical stresses to 20 which they are subjected, but that they may also successfully withstand the mechanical stresses to which they are frequently subjected when in use.

25 A further object of the invention is to reduce practically to a minimum the total number of parts in the appliance.

These and other objects of the invention will be hereinafter referred to and the novel 30 elements and combinations of elements whereby these objects are accomplished will be more particularly set forth in the appended claims. It is to be understood, however, that many modifications and changes 35 may be made in the device shown by way of illustration herein, and the invention is hence to be limited only by the scope of the said appended claims.

In the drawings which form a part hereof 40 and in which like references designate like parts throughout the several views: Figure 1 is a side elevation of a high tension disconnecting switch constructed in accordance with the principles of our invention. Fig. 45 2 is a plan of the same. Fig. 3 is an end elevation of a pair of said switches with an operative connection therebetween.

Referring to the drawings, two line wires 1-2, are therein shown disposed in alinement; the wire designated 1 being connected, for example, to the eye 3 of a stud 4, the head 5 at the inner extremity of which is embedded in an umbrella shaped or petti-

coat insulator 6. Laterally projecting from the opposite side of this insulator, and in alinement with the stud 4, is a pin 7, the extremity of which adjacent the head 5 may be correspondingly headed as at 8; both the pin 7 and stud 4 being rigidly secured in the petticoat insulator.

60 The pin 7 is revolvably mounted in a bearing 9 and the inner extremity of this pin may be provided with a head 10 adapted to prevent its inadvertent removal from the bearing. The pin may be held against longitudinal displacement in the other direction by a collar 11; and it also carries a crank or lever 12, by means of which it may be rotated in its bearing. If desired, a set screw 13, or some equivalent means, may 70 be provided for the purpose of preventing too free movement of the pin 7 and the parts carried thereby.

Bearing 9 is fixedly mounted upon a cross-arm or beam 14; and studs 15 are secured in 75 said arm which serve to rigidly connect it to a similar arm 16. The last mentioned cross-arm carries a bearing 17 similar to bearing 9, except that it is preferable to secure the pin 18, which is mounted in bearing 17, against rotary as well as endwise movement. To prevent longitudinal movement of pin 18 with respect to its bearing the pin may be headed as at 19, and is provided with a collar 20. Pin 18 also carries 80 a petticoat insulator 21 from which projects a stud 4'. The studs 4-4' respectively have secured thereto the switch arms 22-23, the latter of which is provided with spring contacts 24 adapted for the reception of the 85 switch blade 25 therebetween.

90 The insulators 6 and 21 may be of porcelain, or other suitable material.

In Fig. 3 are exemplified means for actuating a plurality of the novel switches simultaneously; the levers 24 of two adjacent switches being connected together by a link 26, so that movement of one of these levers insures movement of both.

100 The operation of the switch exemplified is as follows: Owing to the disposition of the pins 7-18 and studs 4-4', all substantially in alinement, when the device is connected as shown in Fig. 1 to taut line wires, the tension in the said wires exerts no tendency 105 to relatively displace any of the elements of

the switch proper. The cross-arms 14-16 support the weight of the parts and the insulators 6-21 are subject substantially only to a direct pull. One of these insulators 5 is rotatable, being mounted upon the rotatable pin 7, but the other is fixed. The switch arm 22 which is fast upon the stud 4 which projects from the rotatable insulator is also revoluble. By means of the lever 10 24, the blade 25 may be swung into or out of engagement with the spring contacts 24, thereby making or completely interrupting the circuit, at this point. The current flows, let us say, from wire 1 through stud 4, arm 15 22, contacts 24-25, arm 23 and stud 4', to wire 2. By practically no chance can it short circuit from wire 1 to wire 2 when the switch is open, since to do so it would have to perforate, or leap around two petticoat 20 insulators. Switches properly constructed in the manner shown, and with but two insulators, are applicable to circuits of all voltages ranging from, let us say, 2000 to 20,000 volts. The number of insulators, 25 however, may be varied, so that circuits as high as 200,000 volts may be efficiently disconnected by means of switches similar to that herein shown. It is preferred to ground the mechanical connections disposed between 30 the insulators so as to prevent any possibility of a punctured insulator allowing current to flow from one side of the line to the other when the switch is open. The pins 7 and 18 are therefore shown as being ground- 35 ed at 27. Finally, it is sometimes desirable to completely interrupt either a plurality of independent high tension circuits, or the same circuit at two points. In Fig. 3 two 40 rotary switches of the type in question are shown mounted side by side and relatively adjacent each other. The connection between these operating levers enables both to be actuated simultaneously.

The insulators 6 are known in the parlance 45 of the art as "dead ending insulators", and the construction exemplified embodies these insulators, which must be used in any case, directly in the switch proper, reducing to the fewest number of parts a switch applicable 50 to any voltage.

Having described the invention, it is claimed:

1. A high tension disconnecting switch comprising a fixed element and a rotatably mounted conductive element, means for connecting said elements both mechanically and electrically to adjacent alined line wires, the axis of rotation of said rotatably mounted element being in alinement with said line wires, and insulating supporting means for 55 said elements.

2. A high tension disconnecting switch comprising a fixed element and a rotatably mounted conductive element, means for connecting said elements both mechanically and electrically to adjacent alined line wires, the axis of rotation of said rotatably mounted element being in alinement with said line wires, and insulating supporting means for 65 said elements, said insulating supporting means including a fixed insulator and a rotatably mounted insulator.

3. A high tension disconnecting switch comprising a fixed element and a rotatably mounted conductive element, means for connecting said elements both mechanically and electrically to adjacent alined line wires, the axis of rotation of said rotatably mounted element being in alinement with said line 75 wires, and insulating supporting means for 80 said elements, said insulating supporting means including a fixed insulator and a rotatably mounted insulator, the axis of rotation of said rotatably mounted insulator being 85 the same as that of said rotatably mounted conductive element.

4. A high tension disconnecting switch comprising two axially alined petticoat insulators, one of which is rotatably mounted, mechanical connections between said insulators, conductive switch elements carried by 90 said insulators, and means for connecting alined line wires to said insulators.

In witness whereof, we subscribe our signatures in the presence of two witnesses.

ARION S. KALENBORN.
AUGUST J. PAHL.
